REVOLVING DOOR

Edmund Peremi, Manhasset, and Charles Kish,
Elmhurst, N. Y., assignors to General Bronze
Corporation, Long Island City, N. Y., a corpo-
ration of New York

Application January 7, 1932, Serial No. 585,270

38 Claims. (Cl. 20—18)

This invention relates to revolving doors for buildings and has for an object the provision of an improved construction for the pivotal mounting of the individual leaves of the door whereby the leaves are rigidly and firmly supported, and will not sag, but which permits of the ready folding of the leaves, either when the door is to be folded and pushed to one side, or automatically where, as in the case of panic, a rapid exit through both sides of the door is essential. Other objects of the invention relate to improved means for supporting the door so as to permit its being moved more readily to one side when folded and being returned to operative position and centered in such position when it is to be unfolded and set for rotation. Another object of the invention is to provide an improved chain arrangement for releasably connecting the leaves of the door when unfolded. Other objects and advantages will appear from the following description of certain preferred embodiments of the invention which illustrate the principles thereof.

In the accompanying drawings which illustrate such preferred constructions:

25 Figure 1 is a front elevation showing a door with the leaves unfolded and set at right angles in normal operative position, a part of one leaf of the door being broken away and the door enclosure being shown in section.

30 Figure 2 is a fragmentary view in vertical section through the central supporting column of the door, showing parts of the leaves and illustrating the slide which operates the pivot by which the door is centered at the bottom and the plunger for releasing the trolley latch.

Figure 3 is a horizontal section on line 3—3 of Figure 2.

Figure 4 is a plan view of the door with leaves at right angles, the door enclosure being shown in sectional plan. This figure also shows in dotted lines the position of the door when folded and moved to one side.

Figure 5 is a plan view of the floor socket for receiving the central pivot of the door, parts being broken away.

Figure 6 is a vertical sectional view showing the trolley for supporting the door and means for locking the trolley at the inner and outer limits of its travel. This figure also shows in section the hinge supports for the door leaves at the top of the door.

Figure 7 is a plan view of the trolley, its tracks and the trolley locking means, parts being broken away.

55 Figure 8 is a vertical sectional view showing the

hinge supports for the door leaves at the bottom of the door, and showing the bottom door pivot and its floor socket.

Figure 9 is a fragmentary, vertical, sectional view showing parts of the hinge construction taken on line 9—9 of Figure 8. 5

Figure 10 is a horizontal, sectional, view showing the hinge construction for the door leaves taken at the position indicated by line 10—10 of Figure 8. 10

Figure 11 is a vertical section taken on line 11—11 of Figure 10.

Figure 12 is a section similar to Figure 10 showing the door leaves folded.

Figure 13 is a horizontal section showing the parts in the position illustrated in Figure 12, the section, however, being taken slightly below the level at which the section of Figure 12 is taken and on a plane between the two supporting discs. 15

Figure 14 is a horizontal section taken on line 14—14 of Figure 1, parts of the latch blocks being broken away. 20

Figure 15 is a horizontal section on line 15—15 of Figure 16 showing a portion of one of the door leaves on an enlarged scale and illustrating the details of the spring pressed latch mechanism for engaging the chain. 25

Figure 16 is a side elevation of the parts shown in Figure 15, the cover plate being removed.

Figure 17 is a section taken in the position illustrated by line 17—17 of Figure 16. 30

Figure 18 is a detail view in horizontal section showing the edge of one of the door leaves and the weather stripping mounted thereon.

Figure 19 is a view in horizontal section similar to Figure 10, showing a modified construction of means for releasably locking the door leaves in radial positions. 35

Figures 20, 21 and 22 are plan views on a reduced scale showing locking rings used in the modified construction. 40

Figure 23 is a vertical sectional view on line 23—23 of Figure 19.

Figures 24 and 25 are diagrammatic plan views showing respectively the engagement of the locking bolt with the disc and with one of the locking rings. 45

Figure 26 is an end view of the locking bolt.

Referring to the drawings in detail, the door comprises a central supporting column 20 upon which are mounted, by hinged or pivotal connections, the door leaves 21, usually four in number. When the door is in operative position the leaves are set at right angles to one another, as indicated in Fig. 4, but the leaves may be folded up 50

and the door moved to one side, as indicated in dotted lines in this figure. The door is mounted in an enclosure or frame comprising curved side walls 22, a ceiling 23 (Fig. 1) and a floor 24. The 5 ceiling is slotted at 25 to permit the movement of the column to one side. The column 20 preferably comprises a strong supporting tube 30 surrounded by a tubular sheath 31 spaced slightly from the supporting tube 30 and adapted to form 10 a finish for the column and also to form a weather tight engagement with the adjacent walls of the door leaves.

The edges of the door leaves are preferably provided with suitable flexible weathering strips 15 32. Figure 18 shows an improved weathering strip and means for anchoring the same to the door leaves. As shown in such figure, the weathering strip comprises a body 33, preferably of molded rubber and tapering in thickness from its 20 base toward its outer edge. To the flexible edge of the rubber strip is secured a contact strip 34 preferably of felt or the like. The body 33 is anchored to the door by means of a channel member 35 of metal or wood in which is formed a Y-shaped groove 36. The rubber body 33 is formed 25 with a base having diverging flanges 37 adapted to fit in the branches of the Y-shaped groove. Screws 38 may be provided at intervals as an additional means for securing the rubber strip in the 30 channel member 35. The construction described provides a very firm and durable means for attaching the flexible weathering strip to the door leaf.

The door is suspended from above by a trolley 35 construction shown more particularly in Figures 6 and 7. A track comprising a pair of parallel channel shaped rails 40 is mounted above the ceiling 23. Mounted to travel on the rails is a trolley comprising a frame 41 supported by wheels 42. The frame includes a transverse channel shaped member 43, supported upon which is a metal cup 44. The cup has a central opening 45 through it around which is an upwardly projecting flange 45. Mounted in this cup and around 45 this flange 45 is an annular block of rubber or other flexible material 46 upon which is mounted a flanged ring of metal 47 which carries a ball or roller thrust-bearing 48. Supported by bearing 48 is a collar 49 which is fixed to the upper end 50 of the supporting tube 30 of the door supporting column. The entire weight of the door is thus carried by the thrust-bearing 48 which permits free rotation of the door. The annular rubber block 46 provides for a limited amount of universal movement of the door supporting column 55 with relation to the trolley and its tracks so as to permit the door to center itself with relation to its enclosure, and to rotate therein without binding, in case there is any imperfection of alignment. It also permits of the proper engagement of the bottom pivot of the door with the floor socket. Universal movement of the door column with respect to the trolley may be obtained in other ways, 60 such as by the usual gimbal bearings, but the rubber block described provides ample freedom of movement for this purpose and is extremely simple and involves the use of a minimum of parts. Furthermore, no lubrication is required at 65 that point, as would be necessary in the case of gimbal bearings. The rubber block is held firmly between the outer wall of the cup 44 and the inner flange 45 thereof, so that it will support the weight of the door without undue spreading. At 70 the same time enough clearance is permitted to

provide for the necessary movement of the column. The collar 49 may be fixed to the tube 30 in any suitable manner, for instance, by means of interengaging screw threads and the locking set screw 50. This arrangement permits of a 5 limited vertical adjustment of the tube with reference to the collar so as to raise or lower the door slightly, as may be necessary to make it properly contact at ceiling and floor.

Two latches are provided, one at about the 10 center of the track for the trolley, and one at one end of said track. One of these latches 60, is arranged to lock the trolley at its central position with the door column in alignment over the central floor socket, thereby permitting the 15 bottom pivot of the door to be readily inserted in such socket; while the other latch 61 locks the trolley in its lateral position with the door folded at the side of the door opening as shown in dotted lines in Figure 4. The latches 60 and 20 61 are of similar construction and each comprises a base 62 which is preferably adjustably mounted on the track structure and secured in adjusted position by bolts 63, passing through elongated slots 64 in the track structure. Each 25 support 62 is provided with a stop 65 adapted to be engaged by the end of the trolley to limit the travel thereof. Each of the supports carries a pair of brackets 66 between which are pivoted the latch arms 67. Each latch arm 67 is 30 provided with a cross-head 68 at the ends of which are mounted screws 69 which engage the top flanges of the tracks 40 and limit the downward movement of the arm 67. On the end of each arm is a lug 70 which has a vertical face 35 on the side towards the latch support which is adapted to engage the face of a latch plate 71 on the trolley and hold the trolley at the limit of its movement, while the other face of the lug is inclined as indicated at 72 so as to engage 40 and ride over the inclined face 73 on the trolley latch plate when the trolley is being pushed towards the latch. It will thus be seen that when the trolley is being moved into latching position the face 73 will engage and lift the lug 70 and 45 arm 67, the latch riding over the trolley latch plate 71 and engaging the latter by gravity when the trolley reaches the limit of its movement in engagement with the corresponding stop 65. Either latch may be adjusted longitudinally by 50 loosening the bolts 63 and sliding the support 62 with relation to the track, such adjustment moving both the stop 65 and the latch arm lug 70 so that these two members retain their fixed 55 relationship and engage and hold the trolley firmly in the desired position.

In order to release the latches the supporting tube 30 of the door has a plunger 80 slidably mounted in its upper end, such plunger terminating in a flanged head 81. Each of the arms 60 67 has a pair of ears 82 projecting from its end between which is pivoted a detent 83. The latter has a nose 84, adapted to be engaged by the flanged head 81, and a weighted arm 85 adapted to hold the detent normally in the position shown 65 in Figure 6 with the nose 84 projecting over the head 81. Upon lifting the plunger it will be seen that the engagement of the head 81 with the nose 84 will lift the latter, which will carry with it the arm 67 and disengage the lug 70 from the edge of the trolley latch plate 71 thereby releasing the trolley and permitting it to be moved along the track. Such movement, however, will soon take the flanged head 81 out 70 of engagement with the nose 84, thereby per- 75

mitting the detent and arm 67 to fall. The lug 70 drops upon the top of the trolley plate 11 and when the trolley is moved far enough, so that the latch plate clears the lug 70, the arm 67 will fall until the screws 69 engage the top of the track in which position the latch will stand ready to be re-engaged by the trolley when the trolley is returned to its initial position. When the trolley reaches the other end of its travel, it will be similarly engaged by the corresponding latch 61 and this latch may be released by moving down the plunger 86 until the flanged head 81 passes the nose 84 which it may do on its downward movement, as it will press down on the nose and raise the weighted arm 85 until the flanged head has passed the end of the nose, whereupon the weighted arm 85 will restore the detent to its original position and the nose 84 will project over the flanged head 81. Upon lifting the plunger and head the latter will lift the nose 84 and thereby release the latch.

The plunger 80 may be raised and lowered in any suitable manner, preferably by means of a rod 90 which passes downwardly through the tube 30 to a slide 91, (Fig. 2,) mounted at some convenient point in the door column. The slide 91 may be actuated in any suitable manner as by means of a stud 92 projecting through a bayonet slot 93 in the side of the column. Stud 92 may, if desired, be provided with a socket 94 in its head for engagement by a key or handle by which it may be more readily manipulated.

The slide 91 is also preferably utilized to operate the bottom pivot of the door by means of downwardly extending rod 95, which has at its lower end a head 96 (Figure 8). A sleeve 97 slides in the lower end of the tube 30 and is provided at the top with a flange 98 which overlies the head 96. Secured in the sleeve 97 is the shank 99 of the bottom pivot 100, the latter preferably terminating in a tapered portion 101. With this arrangement it will be seen that the same movement of the stud 92 and slide 91 which withdraws

40 the bottom pivot from its socket in the floor will raise the head 81 so as to release the latch and permit the door supporting trolley to be moved.

When the door is set in central position in its enclosure, the bottom pivot 100 is received in a socket set in the floor. Any suitable socket may be employed, but I preferably utilize the improved socket illustrated in Figures 5 and 8. In the construction shown, a cup 110 is set into the masonry of the floor, this cup having near its upper end an enlargement terminating in a flange 111 so as to provide a circular recess. Mounted in the recess is a socket plate 112 which has a hole 113 therein which receives the bottom pivot 100. The hole 113 is made slightly off-center with reference to the circumference of the socket plate, as shown in Figure 5 so that by rotation of the socket plate in its recess the position of the hole 113 may be varied slightly with respect to the true center of the floor socket. In this way a limited adjustment is provided for, and the hole 113 may be brought into proper alignment to receive the bottom pivot of the door. This is particularly useful in compensating for slight inaccuracies in setting the socket in the floor. The

70 socket plate may be secured in its recess in any desired position by means of a number of equally spaced screws 114. The cup 110 may be fitted with a readily removable receptacle 115 which will catch any dirt entering the socket and which 75 may be taken out and emptied by removing

the socket plate. This arrangement avoids the necessity for laboriously digging out dirt which may accumulate in the socket on occasions when the door is collapsed and moved to one side and the socket is open. Another socket (not shown) is provided near the side of the door enclosure in proper position to receive the bottom pivot of the door when the door is folded and moved to the position shown by dotted lines in Figure 4.

The leaves of the door are pivotally supported from the central column in the following manner. Mounted at spaced points upon the column, preferably near the top and near the lower part thereof, are similar hinge or pivotal supports (Figures 6 and 8). Each of these supports comprises a pair of discs 120, 121, firmly secured to the supporting tube 30 of the central column in any suitable manner, as by means of flanges 122 and 123 fitting the supporting tube and secured thereto by means of screws 124. The bottom and top hinge constructions of the door are substantially identical except that they are inverted with respect to one another. Considering specifically the bottom hinge construction shown in Figures 8 to 13, inclusive, it will be seen that the disc 120 is circular in form and the disc 121 is slightly larger than the disc 120 and is provided with a flange portion 125 which forms a circular recess receiving the disc 120. The periphery of the disc 121 is of a somewhat angular outline as 30 appears in Figures 10, 12 and 13, and at each of the angles a vertically extending recess or notch 126 is formed, for a purpose to be explained. Each of the discs has cut through it a pair of double lobe cam grooves or tracks, the grooves 35 in the disc 121 being indicated at 127 and the grooves in the disc 120 being indicated at 128. Between the discs is preferably placed a sheet of metal 129 which prevents communication between the grooves in the respective discs. 40

The disc 121 has fixed in it two pairs of pintle studs 130 and 131 which project from its upper surface as shown in Figure 11. Disc 120 has two pairs of similar downwardly projecting pintle studs 132 and 133. The disc 121 also carries two 45 fixed studs 134 arranged at opposite ends of a diameter near the periphery of the disc and projecting upwardly therefrom, and the disc 120 carries two corresponding downwardly extending fixed studs 135 arranged at opposite ends of a 50 diameter at 90° to the diameter at the ends of which studs 134 are arranged. Each of the door leaves has hinge fittings 140 set near the bottom thereof and 141 set near the top thereof. The hinge fittings 140 of two of the diametrically 55 opposite leaves of the door are provided with hinge ears 142 which overlie the disc 121 and which are provided with recesses 143 adapted to engage the pairs of studs 130 and 131, respectively, when the doors are unfolded to their normal radial position with respect to the axis of the door. The hinge fittings 140 mounted at the lower parts of the other two diametrically opposite door leaves are provided with hinge ears 144 which lie beneath the disc 120 and are adapted to engage the pair 60 of studs 132 and 133, respectively, when the door is unfolded as shown in Figure 10. The lower hinge fittings of each of the first named pair of door leaves is provided with a stud 150 carrying a roller 151 adapted to move in one of the cam grooves 127 in the disc 121. Each of the hinge fittings in the other pair of door leaves is provided with a stud 152 carrying a roller 153 travelling in one of the cam grooves 128 in the disc 120. The hinge fittings 141 at the top of the door are con- 75

structed in the same way as the fittings 140 except that they are inverted. In moving the door leaves from the unfolded or right angle position shown in Figure 10 to the folded or collapsed condition 5 shown in Figure 13, it will be seen that each door leaf is rocked about one or the other of its pair of pintle studs 130, 131, 132 or 133 as the case may be and that during this rocking operation the roller mounted on the stud carried by the door fitting travels in the corresponding part of its cam groove in either the disc 120 or the disc 121 as the case may be. In this way the door leaves may be moved from a position at right angles to one another to a position in which all the door leaves 10 are in substantial parallelism as shown in Figures 12 and 13. The position of the door leaves with respect to the discs 120 and 121 when the door leaves are folded or collapsed is maintained by engagement between one of the ears on each door 15 leaf hinge fitting and its corresponding pintle stud in the proper disc and by the engagement of the stud rollers mounted in the door leaf hinge fittings with the walls of the cam grooves in the discs. When the leaves are moved to right angle 20 or radial position as shown in Figure 10, however, it will be seen that the rollers on the door studs are each located at one of the cusps in the cam grooves in which position the roller does not extend the full width of the groove because it is 25 necessary to provide a clearance at this point of intersection between the two curved cam groove lobes. Accordingly, in this position of the door leaves, play would be allowed between the door leaves and the central column, and the ears on 30 the door leaves might move slightly out of engagement with the pintle studs on the discs. This movement, if permitted at the top hinge mounting of the door leaves, would permit such leaves to sag at the top away from the column and thereby 35 prevent the door from fitting its enclosure properly and rotating freely. In order to hold the door leaves at all times in proper alignment and in true parallelism with the central column, provision is made of supplemental means to support 40 the door leaves and maintain firm contact between the pintle studs and the ears on the door leaves when the door leaves are at the right angular unfolded position of Figure 10. These means comprise a block 160 pivoted in a recess 45 in each door leaf hinge fitting and adapted when the doors are in the right angular position of Figure 10 to engage and bear against one of the fixed studs 134 in the discs 121, or 135 in the discs 120, as the case may be. The blocks 160 are arc-shaped at the back as shown at 161 (Figs. 10 and 12) and are provided with V-shaped faces 162 which engage the studs 134 or 135. The blocks 160 are mounted on pivots 165 rotatably mounted 50 in the door hinge fittings as shown in Figure 8. Bullet catches 166 are also preferably mounted 55 in the door hinge fittings, these catches engaging in one or the other of three recesses 167 formed in the adjacent faces of the blocks 160. The engagement of the bullet catch in one or the other 60 of these recesses serves to releasably retain the block either in the central position shown in Figure 10 or in one or the other of its partially rotated positions as shown in Figure 12. When the door leaves are set at right angular position as 65 shown in Figure 10, the blocks 160 bear against their corresponding studs 134 or 135 and thereby prevent any movement of the door leaves out of their true positions in close contact with the central column. The ears at the top of the door 70 leaves are also prevented from moving away from 75

the corresponding pintle studs. When the door is folded, however, as shown in Figures 12 and 13, the blocks 160 are partially rotated by contact between the studs 134 and 135 and the corresponding walls of the V-shaped faces 162. The movement of the blocks out of contact with the studs 134 and 135 takes place at the same time that the rollers on the door studs move away from the cusp positions in the cam grooves and move into the curved parts of those grooves where they fit closely between the groove walls and thereby support the door leaves in proper alignment. When the door leaves are restored to their right angular position, the tilted walls of the V-grooved faces of the blocks 160 engage their respective 15 studs 134 and 135 and are moved back to the engaging positions shown in Figure 10. The bullet catches offer no substantial resistance to the movement of the door leaves but serve to maintain the blocks 160 in one or the other of the 20 positions to which they are moved by engagement with the pins 134 and 135 and maintain the blocks in such positions until the door leaves are restored to right angular position. In this way the possibility of the blocks jarring out of position when 25 the door leaves are folded as shown in Figure 12 is prevented and the blocks are at all times in a position to properly engage the studs 134 and 135 when the door leaves are moved back to right angular position. 30

It will be seen that in order that the door leaves may be closely folded as shown in Figures 12 and 13, it is necessary that recesses 170 be provided in the door leaves for the reception of certain of the pins 134 and 135 which would otherwise engage the two outermost of the folded leaves and prevent complete folding of the same into parallelism. These recesses have to pass entirely through the door so that any of the door leaves may be folded in either direction to the limit of 40 permissible movement. In order to prevent drafts from blowing through such recesses, spring actuated flaps 171 are mounted on pins 172 in the door leaves. These flaps will yield in either direction when engaged by one of the pins 134 or 135 45 so that they do not interfere with the folding of the doors while they at all times prevent the passage of air through the openings in the door leaves. The door leaves are also provided with recesses 173 for clearing the hinge ears 142 or 50 144 on adjacent leaves, when the leaves are folded as shown in Figure 12. In order to prevent the passage of drafts through such recesses, weathering plates 174 (Figs. 10 to 13) are provided which extend across such recesses. The edges of the 55 plates lie close to the central column when the door leaves are arranged in radial position (Fig. 10).

For the purpose of locking the door leaves in unfolded or right angular position, retractable 60 bolts 180 are provided for engagement in the recesses 126 in the peripheries of the discs 121. The ends of the bolts are preferably of wedge shape, the recesses being correspondingly shaped, and the bolts are yieldingly urged into their recesses 65 so that upon the application of sufficient pressure against any door leaf while another or others of the leaves are held stationary, the bolt will ride out of its recess and permit the door leaf to be folded. This permits the door leaves to be folded 70 by the mere application of pressure without any manual releasing of latches or the like, and whenever it is desired to fold the door leaves it may be done in this way. The principal object of the yielding arrangement of the bolts, however, is 75

to make the door "panic-proof" whereby in case of an emergency if many people try to leave the building by the door and press upon diametrically opposite leaves of the door at the same time, the door leaves will yield and the door will fold thereby permitting the crowd to pass out through both sides of the door. In a construction of this nature, it is necessary that the resistance of the bolts to the folding of the door leaves will be considerable so that the door leaves will not be folded accidentally by the application of light force or by wind pressure. This may be accomplished by the use of sufficiently strong springs for resisting the movement of the bolts. Owing to the necessity for this considerable resistance, it is desirable to have manual means for releasing the spring tension when the bolts are to be withdrawn for the normal folding of the door, and the following construction has been provided for this purpose. Each bolt 180 has a hollow shank 181 into the end of which screws a flanged bushing 182. Passing through the bushing is a rod 183 which has a head 184 slidably in the recess in the bolt and adapted at one end of its movement to engage with the inner end of the bushing 182. The head 184 carries a pin 185, the ends of which project into slots 186 in the shank of the bolt, thereby preventing the head from rotating with reference to the bolt. As the bolt itself is rectangular and cannot rotate with respect to its housing, it will be seen that the rod 183 cannot rotate. The outer end of the rod 183 is screw threaded and screws into a nut 187 in which is formed a longitudinal groove 188. Compressed between the flange on the bushing and the nut 187 is a strong coiled spring 189 which may be put under a desired degree of initial compression by adjusting the nut 187 on the threaded end of the rod 183. Fixed on the outer end of the rod 183 is a collar 190 and fixed at an intermediate point on the rod is a stop ring 191. The nut 187 may be adjusted longitudinally on the rod between the collar and the ring. For effecting this adjustment a disc 192 is provided which has a key 45 engaging in the slot 188. The edges of the disc project through slots 193 in the sides of the door fitting (Fig. 10) and the surface of the disc is preferably knurled so that it may be rotated. In this way the nut 187 may be readily turned so as to adjust the tension on the spring 189. The outer end of the rod 183 and the collar 190 bear against a cam 194 rotatably mounted in a recess in the door fitting and having an exposed socket 195 adapted to receive a key (shown in dotted lines in Figure 10) by which it may be rotated. The cam has a cylindrical face portion 196 and a flattened face portion 197, and a bullet catch 198 may be provided for engagement with one or the other of two recesses in the cylindrical surface of the cam so as to yieldably lock the cam either in the position shown in Figure 8 with a portion of the cylindrical surface of the cam bearing against the rod and collar or in a position shown in Figure 8 in which the flat of the cam faces the end of the rod and collar. A stop 199 is also provided in the cam housing which positively stops the cam at the limits of its rotative movement. When the cam is in the position shown in Figure 8, the rod which of course carries the spring abutment nut is held in such position as to force the bolt into its recess in disc 121 and the bolt can only be forced from its recess by pressure sufficient to compress the spring 189. When the cam is turned to the other po-

sition, however, the spring and bolt assembly may be retracted freely so as to permit free swinging movement of the door leaf.

Owing to the fact that the door leaves have a pivotal movement about one or the other of the pintle studs which are displaced from the central axis of the door, it will be seen that the path of movement of the nose of the bolt 180 after leaving its recess 126 will be approximately on the arc indicated by the broken line A in Figure 10. This fact, coupled with the fact that the periphery of the disc 121 is of generally angular form rather than circular, will cause the nose of the bolt to move away from the periphery of the disc, rather than in contact with it through a substantial arc, as would be the case if the periphery of the disc were circular and the door leaves were pivoted to move about an axis concentric with the axis of the discs. Accordingly, excess friction and wear of the parts is avoided because the noses of the bolts quickly move entirely out of contact with the periphery of the disc.

The stud 92 as shown in Figures 2 and 3 is preferably arranged so that when the door leaves are at right angles, one of the leaves will conceal the stud, opening 229 being provided in the leaf for this purpose. Owing to the manner in which the leaves swing upon one or the other of the pintle studs, the motion of the leaf will be away from the central column to a sufficient extent to enable the edges of the opening in the leaf to clear the head of the stud. When the leaves are folded, the stud can then be manipulated in the manner described to withdraw the bottom pivot from its socket in the floor and release the latch which holds the door trolley in position. The concealing of the stud improves the appearance of the door and also prevents manipulation of the same to release the bottom pivot and trolley latch while the door is in operating position.

The manner in which the faces of the door leaves move towards and away from the surface of the column when the doors are swung about the pintle studs and the formation of such faces in concave shape with a curvature to fit the surface of the column, enables these faces to be brought into close contact with the column surface when the leaves are set in operating position, thereby making a weather tight closure at this joint.

The engagement of the bolts 180 in the recesses 126 in the discs 121 will in many instances be sufficient to maintain the door leaves in their right angular position without the use of any additional holding means for the door leaves. If, however, it should be desired to provide an additional means for connecting the door leaves to one another to resist undesired collapsing of the door, any well-known releasable chain or link arrangement may be utilized. For example, the chain arrangement shown in Figures 14 to 17 may advantageously be utilized, this arrangement presenting certain valuable features of novelty and being applicable to any other type of panic-proof revolving door as well as to the construction above described.

In the construction shown in Figures 14 to 17, a single chain 200 is employed, the ends of which are fixed to one of the door leaves at the points 201, the chain passing without break through recesses in the other three door leaves. At three points in the chain corresponding with the positions of the other three door leaves when the leaves are at right angles, substantially diamond-shaped links 202 are inserted and yielding engag-

ing devices are provided in the door leaves for yielding engagement with these diamond-shaped links which thereby serve to hold the door leaves normally at right angles but permit them to be moved upon the application of sufficient pressure. The yielding means in the door leaves comprise channel-shaped fittings 205 set in recesses in the leaves, each channel-shaped fitting being provided with a removable cover plate 206 secured to the fitting by screws 207 or in any other suitable manner. Mounted to slide in the channel fitting is a frame 208 which may be adjusted longitudinally by means of the screw 209 which may be rotated by a disc 210 having sockets therein for insertion of a pin. Slidably mounted in the frame 208 is a latch block 211. Mounted in a cross member 212 of the frame is a screw 213 which carries a spring abutment 214 between which and the latch block 211 is mounted a compression spring 215. The initial compression of the spring 215 may be determined by adjustment of the screw 213. The face of the latch block 211 is notched or grooved as indicated at 220 for engagement with one of the diamond-shaped links 202. Slidably mounted in the frame 208 outside of the diamond-shaped link 202 is an abutment block 221 which has a grooved face 222 for engagement with the diamond-shaped link. A cam 223 mounted on a pivot 224 in the frame 208 is arranged to engage and support the abutment block 221. Cam 223 has a face 225 arranged to hold the abutment block in advanced position and it has a flat face 226 which, when the cam is rotated a quarter turn permits the block 221 to move away from the latch block 211. The cam may be rotated in any suitable manner as by means of a pin (not shown) inserted in a socket 227, a slot 228 being provided in the cover plate 206 for the insertion of the pin. When the block 221 is held in the advanced position shown in Figure 15, the door leaves can only be folded by applying a pressure great enough to depress the latch bolt 211 to an extent sufficient to permit the points of the diamond-shaped link to clear both the abutment block 221 and the latch block 211. By adjusting the screw 213 any desired compression of the spring 215 may be secured and the resistance to the disengagement of the link 202 from the latch block made as great as is desired. If it be desired, however, to fold the door in the ordinary manner and without the application of considerable pressure, the cam 223 is rotated so as to permit the retraction of the abutment block 221. It will now be seen that the door leaf may be disengaged from the diamond-shaped link by the application of only sufficient pressure to cause the latch block to be retracted a distance equal to one half of the movement which would be required of such latch block in case the abutment block were held in its forward position by its cam.

The use of the slidable frames 208 carrying the devices for engagement with the chain 200 enables the chain to be tightened up at any time it may become slack by moving out one or all of the frames 208 by adjustment of the screws 209.

In the use of the chain arrangement described, the door leaves may be collapsed as soon as any one of the diamond-shaped links 202 moves out of engagement with the latch means on the corresponding leaf. As soon as this takes place, the other leaves may be folded by the doubling up of the stretches of chain between such remaining leaves. As long as all three of the diamond-shaped links are in engagement with their

respective leaves, however, all of the leaves are firmly held in proper angular relationship.

It is evident that the construction described will permit the door leaves to be folded into two parallel pairs placed at 180° from one another, as well as permitting all four of the door leaves to be folded parallel, as shown in Figures 12 and 13. As stated, the particular novel chain arrangement described, may be utilized in connection with the door construction illustrated and described or with any other suitable folding leaf door construction.

In the construction of door shown in Figures 1 to 13, it will be seen that each leaf of the door is releasably locked in radial position by its own bolt mechanisms which engage notches in the discs 121 fixed to the central column. In the event of panic each leaf is therefore capable of being folded independently by the application of pressure thereto, but the folding up of one leaf will not release the bolt mechanisms on the other leaves. The necessary force must therefore be applied to each leaf to overcome the resistance of the bolt mechanisms of that leaf before such leaf will collapse. In Figures 19 to 26, inclusive, I have shown a modified construction of the door, such that as soon as the resistance to movement of any one of the leaves has been overcome, all of the leaves are immediately released so that they are all free to collapse or fold simultaneously. In this way free passage through the door is instantly provided, and there is no possibility of the door becoming jammed or interfering in any way with the free exit of a crowd of people trying to get through it rapidly.

Referring to Figures 19 to 26 in detail, it will be seen that the construction is generally similar to that shown in Figures 1 to 13. The door is provided with a central column including the tubular shaft 30 on which are mounted pairs of discs 250 and 251, which are exactly similar to the discs 120 and 121 respectively, insofar as the various studs and cam grooves or tracks are concerned, which form the supporting and guiding means for supporting the door leaves and permitting them to fold into collapsed condition.

Each disc 251 is provided with a narrow vertical flange 252 which fits the periphery of the body portion of the corresponding disc 250 and with an outwardly projecting flange 253 of circular outline. Each disc 250 has a similar outwardly projecting flange 254 and these two flanges enclose between them an annular recess 255. Rotatably mounted in the recesses between each pair of discs are three rings 256, 257 and 258, each of which is provided with an outwardly projecting perforated lug 259. Each of three of the door leaves is connected to a pair of these lugs 259 on the corresponding rings at the upper and lower door supports. The connection of each door leaf to its lugs is effected by means of a pivot 260 which connects the lug 259 with an ear or ears 261 projecting from a slide block 262 mounted to slide freely in a recess 263 in the door leaf hinge fitting. It will be seen that the middle ring 257 is connected between a pair of ears 261 on the corresponding slide block, as shown in Figure 23. As will be readily understood, the ear on the top ring 256 will be pivoted to a single ear on the second slide block of twice the thickness of the ears 261 shown in Figure 23, while the lug 259 on the bottom ring 258 will be pivoted underneath a similar double thickness lug on the third slide block. It will be seen that when any of the three door leaves pivoted to one

pair of these rings is swung about its hinge pintles it will cause its rings to be rotated in the recesses 255. Each of the rings is provided with a notch 265, the notches in the respective rings being arranged at 90° intervals with respect to the lugs 259 as shown in Figures 20, 21 and 22. The fourth leaf of the door is provided with a pair of latch bolts 180a which are similar to the latch bolts 180 previously described except as to the shape of the bolt face. Each bolt is provided with an adjustable spring assembly similar to that previously described. The flanges 253 and 254 of each pair of discs 251 and 250 are provided with registering notches 270 adapted to be engaged by one of the locking bolts. Owing to the positions of the notches 265 in the three rings of each set, it will be seen that when the doors are in right angular position, as shown in Figure 19, all the notches 265 will be in registry and will register with the notches 270 in the disc flanges. All of these notches will then be engaged by the locking bolts and all leaves will be held in radial position. Upon applying force to the door leaf carrying the locking bolts, it will be apparent that the bolts will ride out of the notches in the disc flanges, as in the construction shown in Figures 1 to 13, and this will cause the bolts to disengage the notches in the rings, so that all the door leaves will be immediately released and will fold freely to their collapsed position. Likewise pressure on any one of the other three leaves, sufficient to move such leaf out of its right angular position, will rotate the rings to which it is attached and thus force back the latch bolts due to the engagement of the walls of the notches in such rings with the ends of the bolts. This will result in releasing all the other three leaves.

In order that all of the leaves may present substantially equal resistance to collapsing movement, the notches 265 in the rings are made more obtuse than the notches 270 in the flanges of the discs, as shown in Figures 24 and 25, and the said ends of the bolts are provided with obtuse central portions 272 for engagement with the notches in the rings and with more acute portions 271 for engagement with the notches in the flanges. Owing to the fact that the door leaf carrying the bolts 180a rotates about the axis of one or the other pairs of pintles 130, it will be seen that the angle between the plane of the notch walls and the radius of rotation of the door is the angle X in Figure 24. As the axis of rotation of the rings, in the event that any other leaf of the door is first moved, coincides with the axis of the column, it will be seen that the angle between the plane of the notch walls in the rings and the radius through the axis of rotation of the rings is made the same as the angle X described. Thus substantially equal force is required to push back the bolts whether this is done by engagement between the acute bolt faces 271 and the walls of notches 270 or between the obtuse bolt faces 272 and the walls of notches 265.

65 The construction of revolving door described is applicable to doors made of any material, such as bronze, nickel, aluminum, steel or wood, or any combination of such materials and the door enclosure may be of such materials or of such materials in combination with marble or the like.

While we have illustrated and described in detail certain preferred forms of our invention, it is to be understood that changes may be made therein and the invention embodied in other structures. We do not, therefore, desire to limit

ourselves to the specific constructions illustrated, but intend to cover our invention broadly in whatever form its principle may be utilized.

We claim:

1. In a revolving door, a plurality of door leaves, a central column carrying pairs of pivotal bearings fixed with relation thereto, at least one pair of pivotal bearings being provided for each door leaf, pairs of bearing members on the door leaves arranged to cooperate with the pivotal bearings carried by the column, the bearing members on the leaves having bearing contact with the respective bearing members carried by the central column but being separable therefrom, each door leaf being arranged to have pivotal movement about one or the other of a pair of said pivotal bearings without previous circumferential movement, the pivotal axes of the respective pivotal bearings and their cooperating bearing members on the door leaves being spaced from each other and from the axis of the column, whereby, when a door leaf is pivoted about one of said pivotal axes, the pivotal bearing and bearing member corresponding with the other pivotal axis will separate, and means for maintaining each door leaf in assembled relation with respect to the column whereby at least one of the bearing members on said door leaf is maintained at all times in contact with the corresponding pivotal bearing carried by the column. 20

2. In a revolving door, a central supporting column, a plurality of door leaves supported thereby and adapted to extend radially therefrom or to be pivoted with respect thereto, and means at each side of each door leaf providing separable pivotal connections between said door leaf and column permitting said door leaf to be pivoted about an axis parallel with, but spaced from the axis of the column, the means providing pivotal connection between the door leaf and column at one side of the door leaf separating when the door leaf is pivoted about the pivotal axis at the other side of the door leaf and vice versa, and means for maintaining the door leaf in assembled relation with the column, so when a door leaf is in radial position, both pivotal bearing members on the leaf are engaged with the corresponding pivotal bearing members on the column and that at least one of the pivotal bearing members on the door leaf is engaged with the corresponding pivotal bearing member on the column at all times. 45

3. In a revolving door, a central column, a plurality of foldable door leaves carried thereby, a pair of pivotal studs for each leaf mounted on the column, the axes of said studs being spaced from each other at each side of the leaf and being spaced from the axis of the column, pairs of bearing members on each leaf adapted to pivot on the corresponding studs, the pivotal connection between said bearing members and studs being separable, whereby the bearing member and stud on one side of the leaf will separate when the door leaf is pivoted about the stud on the other side of the leaf, and means for maintaining the leaves assembled with respect to the column so when a door leaf is in radial position, both pivotal bearing members on the leaf are engaged with the corresponding pivotal bearing members on the column and that a bearing member on each leaf will at all times be engaged with a stud on the column. 60

4. In a revolving door, a rotatable central column, discs fixed on the column, pintle studs pro-

- jecting from the discs near the column, and door leaves each having portions adapted to bear against and swing about adjacent pintle studs, grooves in the discs outside of said pintle studs and 5 having portions concentric with the respective studs and studs on the door leaves adapted to move in and be constantly confined and guided by said grooves as the doors pivot about said pintle studs, and means in addition to said grooves and the studs working therein for supporting said doors in parallelism with said column when said doors are set in spaced radial arrangement about said column.
5. In a revolving door, a central column, discs 15 fixed on the column, pintle studs projecting from the discs, and door leaves having portions adapted to bear against and swing about said pintle studs, grooves in the discs and studs on the door leaves adapted to move in said grooves as the doors pivot about said pintle studs, and means in addition to said grooves and the studs working 20 therein for supporting said doors in parallelism with said column when said doors are set in spaced radial arrangement about said column, 25 said last named means comprising pins projecting from said discs, and blocks mounted in said door leaves adapted to engage and bear against said pins when said door leaves are in radial position.
- 30 6. In a revolving door, a central column, discs mounted on the column, pintle studs projecting from the discs, and door leaves having portions adapted to bear against and swing about said pintle studs, grooves in the discs and studs on the 35 door leaves adapted to move in said grooves as the doors pivot about said pintle studs, and means in addition to said grooves and the studs working therein for supporting said doors in parallelism with said column when said doors are set in spaced radial arrangement about said column, 40 said last named means comprising pins projecting from said discs, and movable blocks mounted in said door leaves adapted to engage and bear against pins when said door leaves are in radial 45 position, said blocks being pivoted to said door leaves to swing about vertical axes and having V-shaped faces adapted to engage and rest against the faces of said pins nearest to the axis of the column.
- 50 7. In a revolving door, a central column, discs mounted on the column, pintle studs projecting from the discs, and door leaves having portions adapted to bear against and swing about said pintle studs, grooves in the discs and 55 studs on the door leaves adapted to move in said grooves as the doors pivot about said pintle studs, and means in addition to said grooves and the studs working therein for supporting said doors in parallelism with said column 60 when said doors are set in spaced radial arrangement about said column, said last named means comprising pins projecting from said discs, and movable blocks mounted in said door leaves adapted to engage and bear against pins when 65 said door leaves are in radial position, said door leaves having openings extending therethrough to receive said pins when the leaves are folded, and movable weather stops in said openings.
- 70 8. In a revolving door, a central column, discs mounted on the column, pintle studs projecting from the discs, and door leaves each having portions adapted to bear against and swing about adjacent pintle studs, grooves in the discs having 75 portions concentric with the respective pintle studs and studs on the door leaves adapted to move in and be constantly confined and guided by said grooves as the doors pivot about said pintle studs, and means in addition to said grooves and the studs working therein for supporting said doors in parallelism with said column when said doors are set in spaced radial arrangement about said column.
- move in and be constantly confined and guided by said grooves as the doors pivot about said pintle studs, spring pressed bolts mounted in the door leaves and movable in the planes of the leaves towards and from the central door column, and notches in the periphery of at least one of said discs adapted to be releasably engaged by said bolts, said bolts being forced back against said spring pressure by engagement with the walls of said notches upon the application of excessive pressure to said leaves.
9. In a revolving door, a central column, discs mounted on the column, pintle studs projecting from the discs, and door leaves each having portions adapted to bear against and swing about adjacent pintle studs, grooves in the discs having 15 portions concentric with the respective pintle studs and studs on the door leaves adapted to move in and be constantly confined and guided by said grooves as the doors pivot about said 20 pintle studs, spring pressed bolts mounted in the door leaves and movable in the planes of the leaves towards and from the central door column and notches in the periphery of at least one of said discs adapted to be releasably engaged by said bolts, said bolts being forced back against said spring pressure by engagement with the walls of said notches upon the application of 25 excessive pressure to said leaves, and means for manually releasing the spring pressure on said bolts.
10. In a revolving door, a central column, discs fixed to said column near the top and bottom of the door, two pairs of pintle studs projecting from each of said discs, two track grooves formed in each disc, each groove comprising two arc portions intersecting to form a cusp, each of said arc portions comprising circular arcs struck about an axis of one of said pintle studs as a center, four door leaves supported by said discs and having open sided bearings adapted to bear against said pintle studs and having concavely curved edge walls adapted to engage the surface of said column when said door leaves are set in radial position with respect to said column, each door leaf having a stud near the top and a stud near the bottom in axial alignment, each of said studs carrying a roller arranged to move in one of said track grooves, pins projecting from said discs near the peripheries thereof, and movable blocks mounted in recesses in said door leaves adapted to engage with said pins and support said door leaves when the roller studs on said door leaves occupy positions at the cusp points in said track grooves.
11. In a revolving door, a collapsible door leaf assembly, a trolley, means for rotatably suspending said door leaf assembly from said trolley, a bottom pivot for said door assembly, a floor socket therefor, a track above the door on which said trolley runs, whereby said door assembly may be moved from a position central of the door enclosure to a position near one side of the door enclosure when the door leaves are collapsed and latch means for automatically engaging said trolley and holding it in a position in which the axis of the door is centrally aligned with the door enclosure when the trolley is moved to its central position, prior to the engagement of the bottom pivot of the door with its floor socket.
12. In a revolving door, a collapsible door leaf assembly, a trolley, means for rotatably suspending said door leaf assembly from said trolley, a track above the door on which said trolley runs, whereby said door assembly may be moved

- from a position central of the door enclosure to a position near one side of the door enclosure when the door leaves are collapsed and latch means for automatically engaging said trolley and holding it in a position in which the axis of the door is centrally aligned with the door enclosure when the trolley is moved to its central position, prior to the engagement of the bottom pivot of the door with its floor socket, and latch means for automatically locking the trolley at its side position. 5
13. In a revolving door, a collapsible door leaf assembly, a trolley, means rotatably suspending said door leaf assembly from said trolley, a track above the door on which said trolley runs, whereby said door assembly may be moved from a position central of the door enclosure to a position near one side of the door enclosure when the door leaves are collapsed and latch means for automatically 10 engaging said trolley and holding it in a position in which the axis of the door is centrally aligned with the door enclosure when the trolley is moved to its central position, prior to the engagement of the bottom pivot of the door with its floor socket, and latch means for automatically locking the trolley at its side position, and means carried by the door assembly for unlatching either of said latch means. 15
14. In a revolving door, a collapsible door leaf assembly, a trolley, means for rotatably suspending said door leaf assembly from said trolley, a track for said trolley, and latch means for the trolley comprising a movable latch member, a detent movably mounted on said latch member, and a plunger carried by said door assembly arranged to engage and lift said detent and latch member when actuated in one direction and to move and pass said detent without moving the latch member when actuated in the opposite direction. 20
15. In a revolving door, a collapsible door leaf assembly, a trolley, means for rotatably suspending said door leaf assembly from said trolley, a track for said trolley, and a combined latch and stop for said trolley comprising a support adjustably mounted on the track and having a trolley stop thereon, said support also carrying a movable latch member adapted to engage a portion of the trolley and hold the trolley in engagement with said stop. 25
16. In a revolving door, a collapsible door leaf assembly including a central column and door leaves supported thereby, a trolley, means for rotatably suspending said door leaf assembly from said trolley, a track for said trolley, a latch for locking said trolley in a predetermined position, a plunger carried by said door leaf assembly for actuating said latch, and actuating means for said plunger extending through said column to an accessible position and including a member adapted to be manually actuated, said member being arranged to be concealed by a door leaf when said leaf is extended in radial position, but to be exposed when the door leaf is collapsed. 30
17. In a revolving door, a collapsible door leaf assembly including a central column, and door leaves carried thereby, a trolley, and means for rotatably suspending said door leaf assembly from said trolley including a thrust-bearing supporting the upper end of said column and elastic means for supporting said thrust-bearing upon said trolley. 35
18. In a revolving door, a collapsible door leaf assembly including a central column, and door leaves carried thereby, a trolley, and means for rotatably suspending said door leaf assembly from said trolley including a column and door leaves pivotally connected therewith, a retractable bottom pivot for said door leaf assembly, actuating means in said column for raising and lowering said pivot, a stud connected with said actuating means by which the same may be manipulated, said stud projecting laterally through an opening in the wall of said column, one of said door leaves being arranged to conceal said stud when the door leaf is in radial position and to expose said stud when said door leaf is collapsed. 40
19. In a revolving door, a collapsible door leaf assembly comprising a column and door leaves pivotally connected therewith, a retractable bottom pivot for said door leaf assembly, actuating means in said column for raising and lowering said pivot, a stud connected with said actuating means by which the same may be manipulated, said stud projecting laterally through an opening in the wall of said column, one of said door leaves being arranged to conceal said stud when the door leaf is in radial position and to expose said stud when said door leaf is collapsed. 45
20. In a revolving door, a door leaf assembly, means for rotatably suspending the same centrally of the door enclosure, a bottom pivot for the door leaf assembly, a floor socket for receiving said bottom pivot including a member having a hole therein into which said pivot fits, and means for adjusting said member with respect to the socket so as to adjust the position of said hole with respect to the true center of the floor socket. 50
21. In a revolving door, a door leaf assembly, means for rotatably suspending the same centrally of the door enclosure, a bottom pivot for the door leaf assembly, and a floor socket for receiving said bottom pivot, said floor socket comprising a cup set in the floor and a plate adapted to be secured to said cup in various rotated positions with relation thereto, said plate having an eccentrically placed hole therein for receiving said bottom pivot. 55
22. In a revolving door, a door leaf assembly, means for rotatably suspending the same centrally of the door enclosure, a bottom pivot for the door leaf assembly, and a floor socket for receiving said bottom pivot, said floor socket having a removable dirt collecting receptacle therein. 60
23. In a revolving door, a plurality of radially arranged leaves adapted to be collapsed about a central axis and means for releasably holding said leaves in angularly spaced relationship, comprising a single chain having its ends attached to one of said leaves and extending through openings in the other leaves and means at each of said openings for releasably gripping the chain to releasably fix each leaf to the chain. 65
24. In a revolving door, a plurality of radially arranged leaves adapted to be collapsed about a central axis and means for releasably holding said leaves in angularly spaced relationship, comprising a chain having its ends attached to one of said leaves and extending through openings in the other leaves, said chain having enlarged links inserted therein at intervals corresponding to the normal angular intervals between the leaves, and means on each of the leaves, except that leaf to which the ends of the chain are fixed, for releasably engaging said enlarged links. 70
25. In a revolving door, a plurality of radially arranged leaves adapted to be collapsed about a central axis and means for releasably holding said leaves in angularly spaced relationship, comprising a chain having its ends attached to one of said leaves and extending through openings in the other leaves, said chain having diamond shaped links inserted therein at intervals corresponding to the normal angular intervals between 75

the leaves and pairs of grooved blocks yieldingly pressed towards each other carried by each of said leaves, except the leaf to which the ends of said chain are fixed, said pairs of grooved blocks being arranged to releasably engage said diamond shaped links.

26. In a revolving door, a plurality of radially arranged leaves adapted to be collapsed about a central axis and means for releasably holding said leaves in angularly spaced relationship, comprising a chain having its ends attached to one of said leaves and extending through openings in the other leaves, said chain having diamond shaped links inserted therein at intervals corresponding to the normal angular intervals between the leaves and pairs of grooved blocks yieldingly pressed towards each other carried by each of said leaves, except the leaf to which the ends of said chain are fixed, said pairs of grooved blocks being arranged to releasably engage said diamond shaped links, and manual actuating means for relieving the engagement of one of the blocks of each pair from its corresponding diamond shaped link.

25. 27. In a revolving door, a plurality of radially arranged leaves mounted to revolve about a central axis and adapted to be collapsed about said axis and means for releasably holding said leaves in angularly spaced relationship, comprising a single chain having its ends attached to one of said leaves and extending through openings in the other leaves, and means at each of said openings for providing yielding gripping engagement with the chain sufficient to hold the leaves in normally spaced relation during the operation of the door, but arranged to permit collapsing of the leaves upon the application of abnormal pressure thereon, and a manually actuatable release for each of said gripping means.

40. 28. In a revolving door, a central column, a plurality of leaves pivotally supported thereon, a disc carried by the column having a notch therein, a spring pressed bolt carried by one of said leaves adapted to engage the notch in said disc, a plurality of rings carried by said disc, one of which is connected to each of the other leaves of the door, each of said rings having a notch therein, said notches being so located in the rings that all of said notches will register with the notch in the disc and be engaged by said bolt when said leaves are in properly spaced radial positions.

29. In a revolving door, a central column, discs mounted on the column, pintle studs projecting from the discs, and door leaves having portions adapted to bear against and swing about said pintle studs, grooves in the discs and studs on the door leaves adapted to move in said grooves as the doors pivot about said pintle studs, at least one of said discs having a notch in its periphery, one of said door leaves carrying a spring pressed bolt adapted to engage in said notch, a plurality of rings carried by said disc, one ring being pivotally connected to each door leaf, each ring having a notch in its periphery, said notches being so placed as to register with the notch in the disc and be engaged by said spring pressed bolt when said door leaves are in properly spaced radial positions.

70. 30. In a revolving door, a central column, a disc mounted on the column, door leaves supported by the column and arranged to have pivotal movement with respect to said column whereby said leaves may be folded to collapse the door, and spring pressed bolts mounted in the door leaves, said disc and the ends of said bolts having parts

5 formed to cooperate so as to hold said leaves in spaced radial positions around said column, said bolts being forced out of holding engagement with the corresponding portions of said disc upon the application of abnormal pressure to said leaves, each means for applying spring pressure to a bolt comprising a spring, a movable spring holding means therefor adapted to hold said spring under an initial minimum tension, and releasable abutment means for maintaining said spring holding means and the spring contained thereby in position to resist retractive movement of said bolt, each spring, and spring holding means being movable as a unit to and from effective position, and said abutment means being movable to a position permitting free retraction of said unit and corresponding bolt, so as to permit said bolt to be disengaged from said disc without stressing the spring and without modification of the initial minimum tension thereof.

20

31. In a revolving door, a central column, a disc mounted on the column, door leaves supported by the column and arranged to have pivotal movement with respect to said column whereby said leaves may be folded to collapse the door, and spring pressed bolts mounted in the door leaves, said disc and the ends of said bolts having parts formed to cooperate so as to hold said leaves in spaced radial positions around said column, said bolts being forced out of holding engagement with the corresponding portions of said disc upon the application of abnormal pressure to said leaves, each means for applying spring pressure to a bolt comprising a spring, a movable spring holding means therefor adapted to hold said spring under an initial minimum tension, means for adjusting such initial minimum tension, and releasable abutment means for maintaining said spring holding means and the spring contained thereby in position to resist retractive movement 35 of said bolt, each spring, spring holding means, and spring adjusting means being movable as a unit to and from effective position, said abutment means being movable to a position permitting free retraction of said unit and corresponding bolt, so 40 as to permit said bolt to be disengaged from said disc without stressing the spring and without modification of the initial minimum tension thereof.

32. In a revolving door, a central column, a disc mounted on the column, door leaves supported by the column and arranged to have pivotal movement with respect to said column whereby said leaves may be folded to collapse the door, and spring pressed bolts mounted in the door leaves, said disc and the ends of said bolts having parts formed to cooperate so as to hold said leaves in spaced radial positions around said column, said bolts being forced out of holding engagement with the corresponding portions of said disc upon the application of abnormal pressure to said leaves, each means for applying spring pressure to a bolt comprising a coiled spring, a movable spring carrier for said spring comprising abutments for the ends of the spring and means for supporting said abutments in adjusted spaced relation so as to determine the initial minimum tension of the spring, and releasable abutment means for maintaining said spring carrier and the spring contained thereby in position to resist retractive movement of said bolt, each spring and spring carrier being movable as a unit to and from effective position, and said abutment means being movable to a position permitting free retraction 65 of said unit and corresponding bolt, so as to permit 70

said bolt to be disengaged from said disc without stressing the spring and without modification of the initial minimum tension thereof.

33. In a revolving door, a central column, a disc mounted on the column, door leaves supported by the column and arranged to have pivotal movement with respect to said column whereby said leaves may be folded to collapse the door, and spring pressed bolts mounted in the door leaves, said disc and the ends of said bolts having parts formed to cooperate so as to hold said leaves in spaced radial positions around said column, said bolts being forced out of holding engagement with the corresponding portions of said disc upon the application of abnormal pressure to said leaves, each means for applying spring pressure to a bolt comprising a coiled spring, a movable spring carrier for said spring comprising abutments for the ends of the spring, a rod connecting said abutments and having screw threaded engagement with at least one thereof, and means for effecting relative rotation between said rod and spring abutment so as to adjust the initial minimum tension of the spring, each spring carrier and spring being movable as a unit to and from effective position, and releasable abutment means for maintaining said spring carrier and the spring contained thereby in position to resist retractive movement of said bolt, said abutment means being movable to a position permitting free retraction of said unit, and corresponding bolt, so as to permit said bolt to be disengaged from said disc without stressing the spring and without modification of the initial minimum tension thereof.

34. In a revolving door, a central column, a disc mounted on the column, door leaves supported by the column and arranged to have pivotal movement with respect to said column whereby said leaves may be folded to collapse the door, spring pressed detents carried by the door leaves, said disc and detents having parts formed to cooperate so as to hold said leaves in spaced radial positions around said column, said detents being forced out of holding engagement with the corresponding portions of said disc upon the application of abnormal pressure to said leaves, and means for applying spring pressure to each detent, comprising a spring, a movable spring holding means therefor adapted to hold said spring under a predetermined stress and movable with said spring as a unit to a position wherein the effectiveness of the spring to resist folding movement of the associated leaf is reduced and back to a position for restoring the initial effectiveness of the spring while maintaining the stress of the spring substantially unchanged throughout such movement.

35. In a revolving door, in combination, a rotary central support, leaves collapsibly mounted on the central support, one leaf being the dominant leaf and having a latching member carried by it and movable relative to it and engageable with the central support for locking said leaf in substantially fixed normal angular position, and members movable respectively with the other leaves and having interlocking engagement with the latching member of the dominant leaf for locking said other leaves in substantially fixed normal angular positions, said latching member of the dominant leaf being rendered and maintained ineffective by any substantial displacement of any one of the leaves from normal position and thereby causing all of the leaves to be simultaneously unlatched. 15

36. In a revolving door, in combination, a rotary central support, leaves collapsibly mounted on the central support, one leaf being a dominant leaf, a latching member carried by the dominant leaf and movable toward and from the axis of the central support to latch and unlatch said leaf, and means carried by another leaf and having interlocking engagement with the said latching member 25 of the dominant leaf whereby unlatching of the dominant leaf causes the dominant leaf and said other leaf to be unlatched simultaneously.

37. In a revolving door, in combination, a rotary central support, leaves collapsibly mounted on the central support, one leaf being a dominant leaf, a latching member carried by the dominant leaf and movable toward and from the axis of the central support to latch and unlatch said leaf, and means carried by each of the other leaves 35 and having interlocking engagement with said latching member of the dominant leaf and in turn controlling it, the latching member of the dominant leaf being movable to an unlatching position by any substantial displacement of any 40 leaf from normal position to cause all of the leaves to be simultaneously unlatched.

38. In a revolving door, a rotatable central column, discs fixed on the column, pintle studs projecting from each disc near the column, door leaves each having portions adapted normally to bear against the respective studs of an adjacent pair and being swingable directly about either stud of the pair, each disc having guide grooves, each located outside an adjacent pair of the studs 45 and each having portions concentric with the respective studs, and studs on each leaf, each adapted to move in and be constantly confined and guided by one of said grooves as the leaf pivots about said studs. 50
